IRONING BOARD

Chester A. Rich, Cincinnati, Ohio, assignor to The Rich Pump & Ladder Company, Cincinnati, Ohio, a corporation of Ohio

Application January 8, 1935, Serial No. 651

6 Claims. (Cl. 68—19)

This invention relates to an ironing board of the collapsible type, and constitutes an improvement over the device disclosed in the patent of H. J. Gilbert No. 1,644,672.

5 An object of the invention is to provide an ironing board of the character referred to which is extremely simple, inexpensive, and very practical.

Another object of the invention is to provide an ironing board with a collapsible leg and brace structure which will fold completely upon movement of the front leg to a position of lengthwise abutment upon the under face of the table member, the various movable parts assuming positions substantially flat against the table member when 15 folded.

A further object is to provide a leg and brace construction for ironing boards, wherein are eliminated the usual long and undesirable tension rods which extend normally from the front leg 20 to the rear legs, at substantially the knee level of the user and to employ short and sturdy struts or compression members in lieu of such long rods.

The foregoing and other objects are attained 25 by the means described herein and disclosed in the accompanying drawings in which:

Fig. 1 is a side view of the improved ironing board, with the leg and brace structure in the extended or operative position.

30 Fig. 2 is a plan view of the Fig. 1 device shown in the collapsed condition.

Fig. 3 is a perspective view showing the leg and brace structure in a partly collapsed condition, the table member being omitted.

35 In the manufacturing of ironing boards of collapsible type, it has been common practice to rely upon the action of tension rods connecting the front leg with the rear legs, for imparting the necessary rigidity for precluding wobbling 40 of the device when in use. The construction in most of the known devices was such that the tension rods were essential parts of the combination, without which the entire structure would

45 collapse. In other prior constructions, the tension rods could be omitted, with the result, however, that the ironing board would lose the characteristic of rigidity which was necessary to practical use of the device. The present invention

50 contemplates the provision of means in association with a table member, for supporting said table member rigidly in the absence of the customary tension rods, with the result that the device may be constructed with a minimum of parts 55 which will move to a collapsed position easily

and completely without interference with other parts such as the long tension rods.

The present device comprises a table member 5 of the usual shape, which table member has a front end 6, a rear end 7 and a bottom or underface 8. The front end preferably is tapered, as is customary. At a location near the rear end 7 is fixed, by the use of any suitable fastening devices such as rivets or bolts 9, a transverse strip or bracket member 10 which has ears or 10 lugs 12 and 13 depending from the opposite ends thereof. The lugs are perforated to receive suitable pivots 13. Each lug or ear 12 has pivoted thereto a pair of rear leg members 14 and a pair of front leg members 15, the front leg members 15 abutting the inner faces of the ears or lugs while the rear leg members abut the outer faces thereof. The rear legs may be connected by either a rigid or an adjustable cross-piece or leg spacer 16, which will hereinafter be referred to as a rear 20 leg spacer or strain bar. In the present embodiment, the strain bar is constituted of a single length of wood or metal properly proportioned to hold the rear legs at a desired angle relative to one another. The member 16 may be nailed, 25 screwed, or otherwise fastened in place, as indicated at 17.

The members 15 which constitute the front leg may converge, if desired, so as to meet at a fastening point 18, thereby to form substantially a 30 single front leg. It is, of course, evident that the lower ends of the front leg members 15 may be spaced apart, if desired, so as to provide a pair of front legs spaced apart and movable in unison about the pivotal mountings 13. The rear 35 legs also are adapted to pivot about the mountings 13, so as to move into folded relationship with the front leg structure against the bottom or under face of the table portion 5.

As is most clearly illustrated in Figs. 2 and 3, 40 the front leg pieces 15 support, intermediate their upper and lower ends, the opposite ends of a fulcrum bar or rod 19, this rod being located preferably closer to the pivots 13 than to the fastening pin or rivet 18.

45 Unlike other devices of the general character above described, the fulcrum rod bar has fulcrumed thereon a single swinging member 20 which is purposely constructed of resilient material, so as to constitute a bow-piece adapted to 50 be bent or bowed by the user in setting up the ironing board. As the bow-piece is swung about the fulcrum 19, the rear end 21 thereof approaches and seats upon the strain bar 16, preferably in a notch 22 thereof, while the front end 55

23 fails to assume a position behind a stop or abutment 24 unless the bow-piece is sprung or bowed upwardly by the operator to dispose said end 23 in contacting relationship with the under 5 face of the table at a location behind the stop or abutment 24. The stop 24 may be in the form of a block of wood or other suitable material.

To insure proper placement of the rear end 21 of the bow-piece upon the strain bar 16, or into 10 the notches 22 thereof, there are provided the struts or compression members 24 and 25 which converge substantially at a point 26 where a suitable bracket 27 is provided for the purpose of 15 definitely locating the convergent portion relative to the bow-piece 20. The bracket 27 may be nailed, screwed, or otherwise suitably fixed upon the bottom face of the bow-piece as indicated at 28. It is, of course, possible to simply support the portion 26 in a transverse bore that may be 20 formed in the bow-piece at a location corresponding substantially to the location assigned to the bracket 27.

The widely separated rear ends 29 and 30 of the compression members are pivotally supported 25 for movement relative to the rear legs and to the strain bar 16, so that movement of the rear legs toward the front legs results in swinging the bow-piece 20 about its fulcrum 19 toward a position in which the bow-piece approaches the plane of 30 the front leg members 15. Conversely, when the rear legs are moved to recede from the front legs, the bow-piece 20 will swing to a position to which the end 21 contacts the strain bar 16. As stated above, the end 23 of the resilient bow-piece must 35 be manually bowed or sprung into position behind the block 24 after the opposite end 21 contacts the strain bar 16. While the provision of a notch such as 22 enhances the rigidity of the structure when disposed in the extended or oper- 40 ative position, said notch may nevertheless be omitted if desired. It will of course be understood that omission of the notch will require either a change in the length of the bow-piece, or a re-location of the members 16 or 19, to pre- 45 serve the bowing function of the bow-piece 20.

By pivoting the spaced rear ends of the struts or compression members 24 and 25 at or near the adjacent rear legs at points such as 31 and 32, there is eliminated any tendency of the rear legs 50 to twist relatively, especially when a seat or notch 22 is provided for reception of the bow-piece end 21. It will be observed that the struts or compression members 24 and 25 may be made short and sturdy, thereby to enhance the rigidity of 55 the structure. As is evident, the struts or compression members are considerably shorter than the distance between the forward end of the front leg and the plane of the rear legs. By reason of this construction there is eliminated entirely the 60 need of long tension rods such as have been necessary for imparting the desired rigidity to other types of ironing board structures.

When all of the leg members 14-14 and 15-15 are made of strips having a uniform width as 65 shown, all of said members and also the bow-piece 20, assume positions substantially flat against the bottom of the table member when the device is folded or collapsed for storing. Furthermore, there are no long tension rods to spring 70 out of place or become bent during careless handling of the device, and the folding operation is facilitated by the absence of such tension rods. The leg structure cannot collapse accidentally 75 during use because the bowed condition of the bow-piece securely maintains the ends 21 and 23

thereof in forceful contacting relationship with the strain bar 16 and the stop or abutment 24, respectively.

It is to be observed that the entire device is constructed of but ten (10) major parts, each of 5 which is simple and capable of rapid production with the use of ordinary machinery. The present device therefore, may be offered for sale at a price considerably lower than that of other somewhat similar devices of the rigid or ten- 10 sioned type.

What is claimed is:

1. A collapsible ironing board comprising in combination: a table member having front and rear ends and an under surface, a front leg 15 structure comprising a pair of members pivoted relative to the table member adjacent to the rear end thereof, and a pair of spaced rear legs also pivoted relative to the table member adjacent to the rear end thereof, a transverse strain bar 20 connecting the rear legs at a distance from the pivotal mountings thereof, a fulcrum rod supported by the front leg structure at a location remote from the pivotal mountings of the front legs, a resilient bow-piece swingingly supported 25 upon the fulcrum rod, said bow-piece having a front end and a rear end, short and sturdy compression members cooperating to guide the rear end of the bow-piece onto the strain bar, and an abutment on the under surface of the table 30 member, said abutment being located out of registration with the front end of the bow-piece except upon bending the bow-piece.

2. A collapsible ironing board comprising in combination: a table member having front and 35 rear ends and an under surface, an abutment on said under surface near the front end of said table member, a front leg structure pivoted relative to the table member near the rear end thereof, a pair of spaced rear legs also pivoted 40 relative to the table member near the rear end thereof, a transverse strain bar connecting the rear legs at a distance from the pivotal mountings thereof, a fulcrum rod supported by the front leg structure at a location remote from 45 the pivotal mountings of said front leg structure, a resilient bow-piece swingingly supported intermediate its ends, upon the fulcrum rod, said bow-piece having a free front end and a free rear end, short and sturdy compression members cooperat- 50 ing to guide and maintain the rear end of the bow-piece against the strain bar, said bow-piece having an effective length greater than the maximum distance from the strain bar to the abutment on the under surface of the table mem- 55 ber, thereby to require bending of the bow-piece to seat it behind said abutment.

3. A collapsible ironing board comprising in combination: a table member having front and rear ends and an under surface, an abutment on 60 said under surface near the front end of said table member, a front leg structure pivoting relative to the table member near the rear end thereof, a pair of spaced rear legs also pivoted 65 relative to the table member near the rear end thereof, a transverse strain bar connecting the rear legs at a distance from the pivotal mountings thereof, said strain bar including a seat, a fulcrum rod supported by the front leg structure at a location remote from the pivotal mountings 70 of said front leg structure, a resilient bow-piece swingingly supported intermediate its ends upon the fulcrum rod, said bow-piece having a free front end and a free rear end, short compression members cooperating to guide and maintain the 75

5 rear end of the bow-piece against the seat of the strain bar, said bow-piece having an effective length greater than the maximum distance from the strain bar seat to the abutment on the under surface of the table member, thereby to require bending of the bow-piece in order to seat it behind said abutment and maintain the table member fixed relative to the rear legs.

10 4. A collapsible ironing board comprising in combination: a table member having a front and rear end and an under surface, an abutment on said under surface near the front end of said table member, a front leg structure pivoted relative to the table member near the rear end thereof, a pair of spaced rear legs also pivoted relative to the table member near the rear end thereof, a transverse strain bar connecting the rear legs at a distance from the pivotal mountings thereof, a fulcrum rod supported by the 15 front leg structure at a location remote from the pivotal mountings of said front leg structure, a resilient bow-piece swingingly supported intermediate its ends, upon the fulcrum rod, said bow-piece having a free front end and a free rear end, a V shaped compression member having its apex pivoted upon the bow-piece, means for mounting the divergent ends of the V shaped compression member pivotally relative to the rear legs, thereby to provide for lateral bracing 20 of the bow-piece, said bow-piece having an effective length greater than the maximum distance from the strain bar to the abutment on the under-surface of the table member, so as to require bending of the bow-piece to seat it behind 25 said abutment.

30 5. A collapsible ironing board comprising in combination: a table member having front and rear ends and an under surface, an abutment on said under surface near the front end of said table member, a front leg pivoted relative to the table member near the rear end thereof, a pair of spaced rear legs also pivoted relative to the table member near the rear end thereof, a transverse strain bar having a notch intermediate its 35

ends and serving to connect the rear legs and space them apart, a fulcrum means supported by the front legs structure at a location remote from the pivotal mountings of said front leg structure, a resilient bow-piece swingingly supported intermediate its ends upon the fulcrum means, said bow-piece having a free front and a free rear end, a compression member comprising a rod bent into V shape so as to provide two divergent legs and an intermediate connecting portion, means for pivoting said connecting portion upon the bow-piece, means for pivoting the ends of the said divergent legs upon the rear legs of the table member, said V shaped compression member thereby serving to guide the rear 15 end of the bow-piece into the notch of the strain bar and to furnish a truss between the bow-piece and the rear legs of the table member, said bow-piece having an effective length greater than the maximum distance from the notch of the strain 20 bar to the abutment on the under surface of the table member, thereby to require bending of the bow-piece in order to seat it behind said abutment.

25 6. A collapsible ironing board comprising in combination: a table member having front and rear ends and an under surface, an abutment on said under surface near the front end of said table member, a front leg structure pivoted relative to the table member near the rear end thereof, a pair of spaced rear legs also pivoted relative to the table member near the rear end thereof, a transverse strain bar connecting the rear legs, a resilient bow-piece adapted to be flexed and curved between the strain bar and the 30 abutment on the under surface of the table member, a bow-piece fulcrum on the front leg structure to provide for rotation of the bow-piece in a plane which meets the table member at right angles, and means in the form of a strut having 35 a hinge connection with the bow-piece and with one of the rear legs, and meeting both the bow-piece and said one rear leg at acute angles.

CHESTER A. RICH.
